COUNTING AND MARKING METHOD AND MACHINE.

Application filed July 24, 1924. Serial No. 727,936.

The present invention relates to counting and marking methods and machines, and more particularly to methods of and machines for counting the number of sheets of paper or the like that are delivered by a sheet-delivery machine into a lay-boy or other magazine, and for marking or separating the sheets so delivered into bundles or reams, each containing a predetermined number of sheets.

According to the machine disclosed in a copending application, Serial No. 563,274, filed May 24, 1922, the sheets delivered into the lay-boy are counted and separated into reams of 480 or of 500 sheets, depending upon whether one or another counter is used. The separation is effected by paper tags that are automatically inserted between successive reams by mechanism controlled by the counters. The sheets may be delivered into the lay-boy either singly or in multiples and the counters may be adjusted to count by units or in multiples, to correspond, so that the paper tags are always inserted between successive reams irrespective of how many sheets are delivered into the lay-boy at each operation.

When the sheets are delivered into the lay-boy in multiples, however, care must be taken that the said multiples shall be factors of the total number of sheets in the ream, else the count will not be accurate. For example, if the sheets are delivered by fives, the counting and marking will proceed just as accurately and efficiently as though the sheets were delivered one at a time. All that is necessary is that the counter shall be adjusted to count fives, instead of units, and the tags will then be inserted at the end of 100, instead of 500, operations of the 500-sheet-ream counter, or at the end of 96, instead of 480, operation of the 480-sheet-ream counter.

If the sheets are delivered into the lay-boy by threes, for example, however, the 500-sheet-ream counter will not count and mark accurately. The counter will, of course, be adjusted to count by threes; but it will cause a tag to be inserted between the first and the second reams at the end of 167 operations, and the first ream will thus contain not 500, but 501 sheets. A tag will be inserted between the second and the third reams after another 167 operations, so that

the second ream, too, will contain 501 sheets. A tag will be inserted between the third and the fourth reams after 166 operations of the counter, and the resulting third ream will thus contain only 498 sheets. The total number of operations of the counter, corresponding to the three reams, will, of course, be exactly 500; and as each operation of the counter corresponds to a count of three sheets, the total number of sheets thus delivered and counted will total 1500, or exactly three reams. The operation will thus be continued indefinitely in cycles of three reams, the first two reams having one sheet too many, and the third ream two sheets too few.

If the sheets are delivered into the lay-boy six at a time, some of the 500-sheet reams will be found to have four sheets too many, and others three sheets too few; if eight at a time, the excess and the deficiency will be four sheets; if nine at a time, some of the reams will have four sheets too many and others five sheets too few; if eleven at a time, some of the reams will have six sheets too many and others five sheets too few; and if twelve sheets are delivered at a time, the excess number will be four, but the defective reams will lack as many as eight sheets.

480-sheet reams will some of them have an excess of three sheets and others a deficiency of four if seven sheets are fed at a time; an excess of six and a deficiency of three if nine sheets are fed at a time; and an excess of four and a deficiency of as many as seven if eleven sheets are fed at a time.

In paper mills, after the rolls of paper have been produced in the paper-making machines, the next step is to sever the rolls into sheets and to separate the sheets into reams. As many rolls as desired may be operated upon simultaneously in the same machine. To be compelled to restrict the simultaneous operation upon a number of rolls that is an exact factor of the number of sheets in a ream is usually a serious matter. If there are nine rolls of paper available, for example, it would be possible to divide them into reams each having the required number of sheets by performing two distinct operations, first upon five of the rolls, and later upon the other four. But this means a duplication of time and labor.

It is preferred to sever all nine rolls, and to separate them into reams, all in one operation.

The purchaser of the reams will not, of course, object if there are too many sheets in the ream; but it is a different matter when the sheets are too few in number. It therefore becomes necessary to move the tags up or down in the stack of sheets in the lay-boy to correct for the error in the count. This is uneconomical and, furthermore, inaccurate.

An object of the present invention is to provide an improved counting-and-marking method and machine that shall yield bundles or groups of articles each having always the same number of articles, irrespective of the number of articles that may be counted at each counting operation.

Other objects will appear hereinafter and will be particularly pointed out in the appended claims.

The invention will be fully explained in connection with the accompanying drawings, in which Fig. 1 is a diagrammatic view, partly in side elevation and partly in longitudinal section, of a paper-sheet-cutting machine of well-known construction, with the present invention attached thereto; Fig. 2 is a rear view of a stack of sheets as delivered into the lay-boy shown in Fig. 1, marked in accordance with the present invention; Fig. 3 is a side elevation of a portion of the operating mechanism of the tag-feeding devices, the view being enlarged with respect to Figs. 1 and 2 and the parts being shown in the relative positions occupied by them when the tag-feeding devices are ineffective; Fig. 4 is a similar view, with the parts in relative positions such as to render the tag-feeding devices effective to feed the tag; Figs. 3^a and 4^a are similar views, showing further steps in the operation; Fig. 5 is a section, upon the same scale, of a portion of the said operating mechanism, the section being taken generally upon the line 5—5 of Fig. 3, looking in the direction of the arrows; Fig. 6 is a side elevation illustrating a preferred embodiment of the present invention, showing, in dot-and-dash lines, a portion of the machine illustrated in Fig. 1, upon an enlarged scale; Fig. 7 is a section taken substantially upon the line 7—7 of Fig. 11, looking in the direction of the arrows; Fig. 8 is a plan of the intermittently operating tag-feeding device and associated parts, shown enlarged with respect to Fig. 1; Fig. 9 is a side elevation of the structure shown in Fig. 8; Fig. 10 is a front elevation of the counter-containing casing, shown enlarged as in Fig. 6; Fig. 11 is a vertical section of the same, taken substantially upon the line 11—11 of Fig. 6, looking in the direction of the arrows; Fig. 12 is a section taken upon the

line 12—12 of Fig. 11, looking in the direction of the arrows, portions being omitted for clearness; Fig. 13 is a view similar to Fig. 12, showing the parts in relatively different positions; Fig. 14 is a section taken upon the line 14—14 of Fig. 11 looking in the direction of the arrows; Fig. 15 is a view of a detail; Fig. 16 is a front elevation of a portion of the mechanism shown in Figs. 8 and 9; Fig. 17 is a section taken upon the line 17—17 of Fig. 8, looking in the direction of the arrows; and Fig. 18 is a view of a detail.

The machine of the present invention is, for illustrative purposes shown applied to a paper-sheet-cutting-and-feeding machine of well-known type, such as is commonly employed in paper mills to sever the rolls 2 of paper, Fig. 1, that are produced in the paper-making machines, into individual sheets, and to feed and stack the severed sheets into lay-boys 4. Any desired, convenient number of rolls 2 of paper may be operated upon simultaneously in the same machine. Six such rolls are illustrated diagrammatically in Fig. 1. The webs 3 of paper from the rolls 2 are led together to feed rolls 6, by which the paper is advanced to disk cutters 8, which sever the paper into longitudinal strips of the desired width. The severed strips are then advanced by feed rolls 10 and 12 to a rotary cutter 16, by which the strips are severed into sheets of the desired length. Tapes 18 and 20 then feed the sheets into the lay-boys 4, which are automatically lowered from time to time to maintain approximately uniform the level of the sheets that are stacked therein.

The sheets so stacked in the lay-boys 4 are separated into bundles each containing a predetermined number of the sheets. It is customary to separate them into reams of 480 or 500 sheets. According to the invention that is illustrated and described in the aforesaid application, the sheets are counted automatically, as they are delivered into the lay-boy 4; and thin, paper tags 24, Figs. 1 and 2, are automatically inserted between adjacent, predetermined sheets at the completion of each count. The tag-inserting mechanism comprises feed rolls 26 and 27, shown more particularly in Figs. 8, 9 and 17. These automatically advance intermittently, through a guide 28, and between a movable knife 30 and a stationary knife 32 a paper strip 34 that is unwound from a reel 36. The end 38 of the paper strip, is thus intermittently advanced, at the proper time, and becomes inserted between adjacent sheets 104 and 106, Fig. 1, of the stack and, after it is severed by the knives 30 and 32, constitutes a tag 24. The feed roll 26 is mounted upon an end of a bell-crank lever 40, intermediately pivoted at 41, and the

other end of which is spring pressed at 42 to cause the feed roll 26 to maintain the paper strip tightly in engagement with the feed roll 27. The feed rolls 26 and 27 are provided with meshing gears 5 and 7. To advance the strip 34, therefore, it is necessary to rotate intermittently the feed roll 26 only, the feed roll 27 being positively driven by the gears 5 and 7 from the feed roll 26, and the two rolls positively pulling the strip 34 through between them.

The feed rolls 26 and 27 are situated at the rear end of the guide 28, at a point just to the rear of and just below the upper sheets of the stack of sheets in the lay-boy, and the knife 32 is situated at the other end. A shaft 44, situated to the rear of the guide 28, is provided with a gear 126, keyed thereto at 220, which drives the feed rolls

26 and 27 through a train of gearing 128. The train of gearing 128 makes it possible to position the feed rolls 26 and 27 properly, at a distance from the driving shaft 44. By feeding the strip at a point so close to the stack, there is no tendency for the strip to buckle or sag in the guide 28. This obviates danger of the strip getting stuck in the guide, which would prevent the strip from being advanced at all. A lever 31, pivoted at 33, by its own weight presses the strip 34 against a seat 35 in the bell-crank lever, just to the rear of the feed rolls 26 and 27, the better to guide the strip. The shaft 44 may be intermittently rotated by a continuously rotating pawl 46, Figs. 3, 4, 3^a, 4^a and 5, when the latter engages the walls of a recess 48 provided upon a normally stationary collar member 50 that is fixed to the shaft 44. The recess 48 is thus, in effect, provided upon the shaft 44. The pawl 46 is pivotally mounted at 52 upon a collar 54 that is keyed at 55 to a gear wheel 56. The gear wheel 56, with the collar 54 that is keyed thereto, is loosely mounted upon the shaft 44. The gear wheel 56 is driven by a gear wheel 58, Fig. 6, from a gear wheel 60 that is mounted upon a shaft 62. Gear wheels 59 are interposed, as a convenient medium of properly determining the direction and speed of rotation of the gear wheel 56, as is illustrated and described in a copending application Serial No. 664,775, filed September 25, 1923. The shaft 62 may be driven from the shaft of the rotary cutter 16 in any well-known manner, as, for instance, in the manner illustrated in the said copending applications, by a sprocket wheel 64 through the medium of a sprocket chain 66, Figs. 6 and 11, that is mounted over a sprocket wheel 68 provided upon the shaft of the rotary cutter 16. The rotation of the shaft 62 is, therefore, a measure of the number of sheets that are cut by the knife 16 and delivered into the lay-boy 4. The collar 54, that carries the pawl 46, is thus continuously rotated

loosely in a circular path about the shaft 44, from the shaft of the cutter 16, so long as the pawl 46 does not engage the walls of the recess 48. When the pawl 46 does engage the walls of the recess 48, however, it will 70 actuate the recess-carrying collar 50; and the shaft 44, to which the recess-carrying collar 50 is secured, will obviously rotate also, causing the feed rolls 26 and 27 to feed the end 38 of the strip 34 between two adjacent sheets 104 and 106 of the stack, as is illustrated in Fig. 1. The feeding of the strip 34 is therefore controlled by the continuously rotating pawl 46. Rotation of the shaft 44 in the wrong direction is prevented by 80 one or more pawls (not shown) operating, with graduated effect, upon one or more ratchet wheels (not shown) as is described in the aforesaid applications.

The pawl 46 is normally prevented from entering the recess 48 by a gate 70, Figs. 3, 4, 3^a, 4^a and 5, that is provided upon a collar 72 that is loosely mounted upon the reduced end 74 of the shaft 44. In the position normally occupied by the collar 72 upon the shaft 44, the gate 70 overlies or covers the forward wall 49 of the recess 48, as shown in Fig. 3, in the path of the pawl 46. So long as the gate 70 overlies this forward wall 49 of the recess 48, the continuously rotating pawl 46 can not engage this wall 49, but rides idly over the gate. Upon the gate becoming displaced from the position of Fig. 3 to that of Fig. 4, the pawl 46, during its next journey around the shaft 44, will be pressed into the recess 48 by a spring 76. The pawl 46, continuing its rotation, will now carry the recess-containing collar 50 with it, and the latter, being secured to the shaft 44, will cause the feed rolls 26 and 27 to advance the end 38 of the strip 34, as above described. Upon reaching the wall 78, Fig. 4, of the gate 70, the pawl 46 will ride out of the recess 48, as shown in Fig. 3^a, whereupon the shaft 44 will cease rotating, and the strip 34 will be no longer advanced. The forward wall 49 of the recess 48 will thus be left behind the gate 70, in the dotted-line position of Fig. 3^a. The pawl 46 will then again continuously rotate idly, 115 as before. It should be noted that when the pawl 46 leaves the forward wall 49 of the recess 48 behind the gate 70, as just described, the shaft 44 has not quite completed a revolution, for the recess 48 occupied originally the position shown in full lines in Fig. 4, whereas it now occupies the position shown in Fig. 3^a. The revolution of the shaft 44 is completed later, as will shortly be described, to effect the actuation of the movable knife 30.

It will now be necessary to explain how the gate 70 is actuated from the position of Fig. 3 to that of Fig. 4 to uncover the recess 48, and thus permit the pawl 46 to 130

actuate the feed rolls 26 and 27 by engaging the forward wall 49 of the recess 48. The gate 70 is provided with a pin 80 that projects into an elongated opening 82, Fig. 6, provided at one end of a lever 84. The lever 84 is intermediately pivoted at 86, and its other end 88 rides along a cam track 90 of a cam disk 89 that is rigidly secured to a counting disk 92 so as to rotate therewith. The cam track 90 is provided with a recess 94 having a sharp, abrupt shoulder 96, a gradually inclined shoulder 98 and an intermediately disposed wall 100. The counting disk 92 and the cam disk 89 are rotated, step by step, as will hereinafter be described, in the direction of the arrow, Fig. 6. When the sharp, abrupt shoulder 96 reaches the end 88 of the lever 84, a spring 102 will move the lever 84 to cause the end 88 of the lever to engage the wall 100 of the recess 94. The other end of the lever 84 will thus be moved downward, as viewed in Fig. 6, causing the pin 80 to be moved downward also. The collar 72 will therefore be rocked from the position of Fig. 3 to that of Fig. 4, causing the gate 70 to uncover the recess 48. The pawl 46 will then be enabled to cause actuation of the feed rolls 26 and 27, as above described. The downward movement of the lever 84, is, of course, timed to take place at the end of a cycle of operation of the counter; say, after a ream has been delivered and counted. It is not essential that the marker be operated once to every revolution of the cam disk 89, for cam disks 89 having a plurality of recesses 94 may be employed, the location of the recess 94, in each case, controlling the operation of the marker.

It has been pointed out above that the pawl 46 will leave the recess 48 at a time when the latter is in the position of Fig. 3^a, and before the shaft 44 has made a complete revolution. This nearly complete revolution of the shaft 44 is effected in about half the time required to make one delivery into the lay-boy. During this nearly complete revolution of the shaft 44, the end 38 of the strip 34 has been rapidly fed from the rear of the stack, in a direction at a substantial angle to the horizontal direction of feed of the sheets, shown nearly vertical in Figs. 9 and 17, into the path of feed of the next following sheet, which constitutes the first sheet 106 of the next ream. If the end 38 of the strip were fed horizontally forward, or at an angle not sufficiently far from the horizontal, being constituted of thin paper, it might strike the rear of the stack of sheets, and not enter between adjacent sheets at all, thus falling to the floor and failing to mark the separating line between the reams. If fed at an angle so near to the horizontal, furthermore, the tags, if it is succeeded in getting them inserted between the sheets, are frequently carried by the sheet 106 so far in between the sheet 104 and the sheet 106 that it is lost to view, and its function as a marker becomes lost. It is therefore desirable to feed the end 38 of the strip 34 at a substantial enough angle to the direction of feed, so as to avoid having the strip engage the rear of the stack or to become lost between sheets of the stack. If fed at such angle into the path of feed of the sheet 106, the head of the sheet 106 will be sure to strike it and lay it down flat upon the last sheet 104 of the ream just completed; which is readily effected by the thin, flexible character of the strip 34. All possibility of the end 38 of the strip 34 becoming displaced is thus avoided. It is furthermore unnecessary to time accurately the moment when the end of the strip is fed upward, as would be the case if it were fed horizontally, or nearly so, which timing it is necessary to adjust for sheets of different length. In order to insure feeding the strip at such angle, an intermediate portion of the guide 28 is curved, so as to rise nearly vertically, as illustrated in Fig. 17 at 29. The end 38 of the sheet is fed upward for a distance sufficiently great so as to make sure that it will rise above the top sheets of the stack and into the path of travel of the sheet 106.

When the end 38 has thus been laid flat by the sheet 106 upon the sheet 104, it is still too early to sever it from the strip 34, as the severing process might pull it out of place. It is preferable to wait until a number of sheets have been fed forward over the sheet 106; their combined weight then serving to hold the end 38 of the strip 34 in place while it is severed. The number of sheets that shall so be fed forward for this purpose depends upon the length of the wall 100 of the recess 94. The cam disk 89 continuing to rotate, as the counter continues to count the additional sheets so fed forward, the end 88 of the lever 84 will ultimately leave the wall 100 and ride up on the inclined shoulder 98 of the recess 94. The other end of the lever 84 will then be returned upward to its normal position, shown in Fig. 6, carrying the pin 80 upward with it. This will have the effect of returning the gate 70 from the position of Figs. 4 and 3^a to that of Figs. 3 and 4^a, uncovering the forward wall 49 of the recess 48, which at this time occupies the dotted-line position of Fig. 3^a, as explained above. During the next cycle of rotation of the pawl 46 about the shaft 44, therefore, it will engage the forward wall 49 of the recess 48, and thus actuate the recess-carrying disk 50 from the position of Figs. 3^a and 4^a to the position of Fig. 3. Upon the recess 48 being thus returned to the position of Fig. 3, the gate 70, occupying the position shown in Figs. 4^a and 3, will again cause the pawl 46 to leave the

recess 48, and the pawl 46 will again continue to rotate idly, as before. This completes the revolution of the collar 50 and, therefore, of the shaft 44 to which it is secured. Upon the completion of this revolution, the knife 30 will actuate to sever the end 38 from the strip 34, the severed end constituting one of the tags 24. The lever 84 is thus adapted to occupy two positions successively, in one of which it controls the feed rolls 26 and 27 to insert the end 38 of the strip 34 between adjacent sheets of the stack, and in the other of which it causes the knife 30 to sever the end 38 of the strip, these two positions being controlled by the cam disk 89. The mechanism for operating the knife 30 will now be described.

The knife 30 is adapted to be reciprocated in a vertical plane in guides 108, to cooperate with the stationary knife 32, by a lever 110, one end of which is pivoted at 114 (Figs. 8 and 9) and to the other end of which the knife is connected at 112. An intermediate portion 116 of the lever 110 is adapted to be engaged by a rotary cam 118. When the recess 48 is moved by the pawl 46 from the full-line position of Figs. 3^a and 4^a to the full-line position of Fig. 3, the lever 110 is actuated by the cam 118, in opposition to the force exerted by a spring 120 to move the knife 30 upwards, as seen in Figs. 9, 16 and 17, causing the end 38 to become severed from the strip 34. It will be noted, from Figs. 8 and 16, that the knives 30 and 32 are inclined to each other in two planes, so as to provide a very effective, shearing cut. The roll cam 118 is mounted upon a shaft 123 having a gear 124 among the same train of gearing 128 that drives the feed rolls 26 and 27 from the shaft 44. The knife is thus operated in timed relation to the operation of the feed rolls 26 and 27 by the shaft 44, which first operates through nearly a complete revolution to cause the feed rolls to feed the strip 34, and then remains stationary until the desired number of sheets have been fed over the sheet 106, and which finally operates through the remainder of its revolution to cause the roll cam 118 to engage the lever 110, thereby causing the knife to sever the end 38 from the strip 34. The knife is returned to normal position before the shaft 44 comes to rest. The cam roll 118 is adjustable to adjust the time of operation of the knife 30.

Upon the retreat of the movable knife 30, the new end 38 of the strip 34 is left under the stationary knife 32. Owing to the substantially vertical direction of feeding movement of the end 38 of the strip, there would be a tendency for the strip to strike against the knife 32, and prevent further advance of the end of the strip, at the next feed movement of the feed rolls 26 and 27. To pre-

vent this happening, a lever 37 is adapted to pivot, by its own weight, about a pivotal point 39, so as to enter between the two knives 30 and 32, as is illustrated in Fig. 9, thereby engaging the end 38 of the strip 70 and pushing it forward, beyond and between the knives. The next forward feed movement of the feed rolls 26 and 27 will therefore result in advancing the end 38 of the strip in a nearly vertical direction, as before described, and as illustrated more particularly in Fig. 9, to one side of the cutter 32. The lever 37 is forced out of the way of the movable knife 30, at each upward movement of the same, in any desired manner, preferably by the knife 30 directly engaging the projecting portion 11 of the lever 37 in its upward stroke. If the lever 37 is constituted of soft metal, like lead, it will not dull or otherwise injure the knife. The return gravity movement of the lever is limited by an integral projection 13 that is adapted to engage the rear of the knife 32.

It has now been explained how the end 38 of the strip is automatically advanced 55 into position in a direction nearly at right angles to the direction of feed of the sheets so that it may be struck by the first sheet 106 of each new ream and laid flat thereby between adjacent sheets 104 and 106 of adjacent reams, and how it is then severed from the strip 34, the tag 24 being thus left in place to mark the boundary between the two reams. It has been explained that the successive operations of the feeding and severing mechanisms for the strip 34 are controlled by the end 88 of the lever 84, through the recess 94 in the cam disk 89 that is secured to rotate with the counting disk 92. It will be necessary to describe 100 also the operation of the counter.

As has been explained above, the shaft 62 of the counter is driven by the sprocket chain 66 from the shaft of the rotary knife 16. The rotation of the shaft 62 is therefore timed to the rotation of the rotary knife 16 and is therefore a measure of the number of sheets that are cut by the knife 16 and stacked in the lay-boy, as has already been mentioned. The teeth of a pinion 150, Figs. 7 and 11, that may be adjustably connected to rotate with the shaft 62, mesh with gear teeth 152 that are provided upon the periphery of the counting disk 92. The angular movement of the counting disk 92 is thus timed with relation to the operation of the knife 16, and may be measured upon a stationary scale 154, Fig. 6, extending through an arc of approximately ninety degrees. The counting disk 125 92 is visible through an opening 156 in the upper portion 202 of the counter-containing framework, so that the degree of angular movement of the counting disk relative to the casing may be read off upon the 130

scale by noting the position, relative to the scale, of one of six indicators 158, respectively marked 0, 1, 2, 3, 4 and 5, upon the front face of the counting disk 92. The 5 parts are so proportioned that each revolution of the shaft of the cutter 16 may effect an angular movement of the counting disk 92 corresponding to any desired integral number of sheets from zero to 26, 10 depending upon the adjustable connection of the pinion 150 to the shaft 62.

To this end, the pinion 150 is not rigidly secured to the continuously rotated shaft 62, but is loosely mounted thereon. A ratchet 15 wheel 160 is fast to the pinion 150 so as to rotate therewith. The operation of the counting disk 92 is thus controlled by the teeth of the ratchet wheel 160. The ratchet wheel 160 is intermittently actuated through 20 a predetermined angular extent by a pawl 162. The pawl 162 is pivotally connected at 164 to an end of an arm 166 that is intermediately fastened to the shaft 62 so as to rotate therewith. As the shaft 62 25 rotates continuously, therefore, the pawl 162 is continuously rotated in a circular path about the shaft 62 as a center. In some positions of its circumferential movement, the pawl 162 is actuated by a spring 30 168 into engagement with one of the ratchet teeth of the ratchet wheel 160. The ratchet wheel 160 is then caused to rotate with the pawl 162 until a tail 163, Figs. 12 and 18, of the pawl is engaged by an inclined face 35 170 of a cam track 172. The cam track 172 is constituted of the circular surfaces of segmental disks 180, 182 and 184, described below. The pawl 162 is thereupon disengaged from the teeth of the ratchet wheel 40 and rides idly over the cam track 172 until, during the next cycle of its rotation, the pawl is permitted by an abrupt shoulder 174 to be actuated by the spring 168 into engagement with another tooth of the ratchet wheel 45 160. In this manner, the ratchet wheel is intermittently actuated through an arc corresponding to the number of ratchet teeth between the abrupt shoulder 174 and the inclined face 170, and the counting disk 92 is 50 correspondingly controlled in accordance with the degree of actuation of the ratchet wheel. The distance between the abrupt shoulder 174 and the inclined face 170 may be so adjusted as to have between them any 55 desired convenient number of teeth of the ratchet wheel 160. In Fig. 12, this desired number is shown to be three. During each revolution of the pawl 162, therefore, the ratchet wheel 160 will be actuated by the pawl 162 through an arc corresponding to three teeth and will cause the counting disk 60 92, through the pinion 150, to be moved through an arc corresponding to three sheets, as indicated upon the scale 154.

According to the disclosure of the above-

described application, Serial No. 563,274, but one pawl 162 is employed to actuate the ratchet wheel 160 once corresponding to each rotation of the arm 166. By mounting a plurality of pawls upon the arm 166, all 70 of them operating once during each rotation of the arm 166, the arc through which the pawl actuates the ratchet wheel may be reduced without affecting the accuracy of the count, and the wear and tear upon the machinery will consequently be reduced. The 75 drawings show two such pawls, the second one being indicated at 165, pivoted upon the arm 166 at a point 167, diametrically opposite the pivotal point 164. A spring 169 80 performs for the pawl 165 the function performed for the pawl 162 by the spring 164. The pawl 165 is provided with a tail 171 corresponding to the tail 163 of the pawl 162. 85

The pawl 162 will actuate the ratchet wheel 160 through an arc corresponding to three teeth, as above explained, during each rotation of the arm 166. During each such rotation, the pawl 165 will similarly actuate the ratchet wheel 160 through a further arc corresponding to three teeth. During each rotation of the arm 166, therefore, the ratchet wheel 160 will be actuated through 90 an arc corresponding to six teeth, and will 95 cause the counting disk 92, through the pinion 150, to be moved through an arc corresponding to six sheets, as indicated upon the scale 154. This will keep the count accurate, as the sheets are fed by sixes, as illustrated into the lay-boy from the six rolls 2. 100

The step-by-step movement of the counting disk 92 is thus controlled by the action of the pawls 162 and 165, which operate in one direction only, in accordance with the 105 operation of the cutter 16. Upon each revolution of the pawls 162 and 165, the counting ratchet wheel 160 is moved, always in the same direction through a predetermined angle corresponding to twice the number of teeth of the ratchet wheel 160 that are exposed between the abrupt shoulder 174 and the inclined shoulder 170. The counting disk 92 is correspondingly moved. In practice, the ratchet wheel 160 has a tendency to 110 overrun after the pawl 162 has been disengaged from its teeth by the inclined shoulder 170. This overrunning would be communicated, through the pinion 150, to the counting disk 92, which would destroy the accuracy of the count. A friction brake 175 is therefore employed to prevent overrunning of the ratchet wheel 160. As shown in 115 Figs. 10 and 11, the preferred brake comprises two shoes mounted to clamp frictionally between them a hub 177 that is integral with the counting disk 92. The shoes are yieldingly held together against the hub 177 by coil springs 179 that are mounted 120 over rods 181 between one of the shoes of the 125 hub 177 and the 130

brake and nuts 183. The other shoe rests against a portion 185 of the frame work, which prevents rotation of the brake along with the counting disk 92. The frictional effect of the springs 179 is sufficient to prevent over-running of the ratchet wheel 160 and, therefore, of the counting disk 92. The various parts of the counter operate always in the same direction of operation throughout, and they thus operate to just the proper degree.

The degree of angular movement of the ratchet wheel 160 that is effected upon each revolution of the pawls 162 and 165 may be adjusted during the operation of the machine by a handle 176, Figs. 6, 10 and 11. This handle is rigidly secured at 178 to the segmental disk 180, the arc of the segment of which is approximately 120 degrees. Together with the two other, similar, segmental disks 182 and 184, in side-by-side relation, the disk 180 is mounted, upon the shaft 62, as shown in Figs. 11, 12 and 13, the disks 180 and 182 loosely, and the disk 184 fixedly. The intermediately positioned disk 182 is provided upon one face with a pin 186 that projects into an arcuate opening 188 of the disk 180. The disk 182 is similarly provided upon its opposite face with a similar pin 190 projecting into a similar arcuate opening 192 of the disk 184. The disks may therefore be angularly moved relatively to each other about the shaft 62 by means of the handle 176, the pins 186 and 190 riding freely in the respective openings 188 and 192. By moving the handle in the direction of the arrow, Fig. 12, therefore, the distance between the abrupt shoulder 174 and the inclined face 170 may be increased. By moving it in the opposite direction, the distance may be decreased. The predetermined number of counting-disk-controlling teeth of the ratchet wheel 160 that are exposed between the abrupt shoulder 174 and the inclined face 170 may therefore be varied, at will from zero to the number found in an arc of approximately 240 degrees. This corresponds to an intermittent feed of from zero to 26 sheets, corresponding to each revolution of the pawls 162 and 165. The segmental disks 180, 182 and 184 may be maintained in adjusted position by a spring-pressed plunger 194, Fig. 11, engaging in any one of a number of openings 196, corresponding to the adjustable positions of the handle 176. In practice, the handle 176 will be adjusted to the number corresponding to the variable number of rolls of paper 2, or of the superposed webs 3, that at any one time supply material to the machine. Six such rolls are shown in Fig. 1, and the handle 176 will therefore be set to the numeral 6 in Fig. 6, so that six sheets may be registered by the counter disk 92 upon each rotation of the shaft of the cutter 16. Half

reams may obviously be marked by setting the handle 176 to cause the counter to count double, and so for other multiples also.

The scale shown in Fig. 6, with which the handle 176 cooperates, does not exactly harmonize with other parts of the drawings, for it should be spaced for fifty teeth in the ratchet. In its illustrated form, however, it better illustrates the principle of operation; and, obviously, the gearing could be so designed as to render the scale accurate.

The counter may be adjusted during the operation of the machine to count in any desired multiples. If it is desired to count by fives instead of by sixes, for example, all that the operator has to do is to move the handle 176 from the position numbered 6 in Fig. 6 to the position numbered 5, and to permit the spring-pressed plunger 194 to become seated in the corresponding opening 196. As is explained in the introductory remarks, however, not all multiples will yield a strictly accurate ream count, when a particular counting disk 92 is employed. Using the counting disks that are illustrated and described in the above-named application, Serial No. 563,274, some reams may have more than the required number of sheets, and others less. According to the present invention, however, the reams will all have the same number of sheets, though this number may be greater than the number that a ream ordinarily contains.

According to the specific embodiment of the invention that is herein illustrated and described, the counting disk 92 is provided with a number of teeth greater than the number that corresponds to a ream. The count will begin at the indicator 158 that is marked 0 in Fig. 6, and will continue through the indicators marked 1, 2, 3 and 4, which correspond to 100, 200, 300 and 400 sheets, respectively, until the indicator marked 5 is reached, corresponding to 500 sheets. If the multiple according to which the count is made results in a ream containing more than 500 sheets, the counting disk 92 will occupy a position, just at the end of the tag-inserting operation, such that the index 230 will lie between the indicators marked 5 and 0. The counting disk 92 is then bodily moved in the same direction until the indicator marked 0 is opposite the index 230. The count may then be proceeded with just as before, the counting disk 92 being returned to its initial position at the end of each ream count.

For example, if the sheets are to be delivered by sixes, as illustrated, let it be assumed that the 0 indicator 158 is initially placed opposite the index 230, and the handle 176 opposite the numeral 6 in Fig. 6. Six sheets will now be registered by the counter disk 92 upon each rotation of the shaft of the cutter 16. After 83 rotations

of the cutter 16, 498 sheets will have been delivered into the lay-boy 4, and the index 230 will occupy a position corresponding to 498 upon the counter disk 92. After 5 rotations of the counter disk 92, the 5 indicator 158 will have traversed beyond the index 230, the latter, in fact, then occupying a position corresponding to 504 sheets. The tag-inserting mechanism then operates to 10 place a tag 24 upon the top sheet of the 504-sheet ream thus produced. Before starting to count the next ream, however, the counter disk 92 will be bodily moved so as to cause the 0 indicator 158 to register once more 15 with the index 230. Every ream thus produced will contain exactly 504 sheets.

Of course, the principle of operation will be the same irrespective of the number of sheets that are delivered at any one time into the lay-boy. All that is essential is that the arc between the indicators 158 marked 5 and 0 be large enough to accommodate the number of sheets in excess of a correctly counted ream that the machine is likely to produce. It is seldom feasible or 20 desirable to feed more than twelve sheets at a time. The maximum arc required between the indicators marked 5 and 0 for any multiple not greater than twelve, either for a 500-sheet-ream counting disk 92 or a 480-sheet-ream counting disk 92 is an arc corresponding to but six sheets. The excess six sheets will be obtained when eleven sheets are delivered at a time, using a 500-sheet-ream counter, and when nine sheets are delivered at a time, using a 480-sheet-ream counter. Of course, one counting disk 92 may be replaced for another having a greater arc between the indicators 158 marked 5 and 0, if such is desired.

The preferred mechanism for performing the above-described function will now be explained. The counting disk 92 is provided with a circumferential recess 232, shown more particularly in Fig. 14. A pawl 234 is adapted to enter the recess 232 and to engage a shoulder 236 of the recess. The pawl 234 is pivotally carried at the end 238 of a lever 240, and is adapted to be spring-pressed at 25 242 into the recess 232. By actuating the lever 240 upward, therefore, as viewed in Fig. 14, the pawl 234 will be caused to move upward also, forcing the shoulder 236 upward. The upward force thus exerted upon the shoulder 236 will cause the counting disk 92 to be actuated about its pivotal point, in the direction of the arrow, Fig. 14. The upward movement of the pawl 234 is just sufficient to cause the counting disk 92 to be actuated through a small arc such that the indicator 158 marked 0 shall register with the index 230.

For clarity of illustration, the recess 232 is shown in Fig. 11 as provided in a second disk 89 secured to the counting disk 92 by a

By this construction, the end 88 of the lever 84 will be prevented from entering the recess 232 and the pawl 234 from entering the recess 94. In practice, the recess 232 may be provided upon a projection 79 mounted upon the counting disk 92.

It is now necessary to describe the mechanism for actuating the lever 240, upon the end 238 of which the pawl 234 is pivoted. The other end 244 of the lever 240 is pivoted to the frame work of the machine. An intermediate portion 246 of the lever is adapted to be engaged by cam portions 248 and 250 of the arm 166, causing the lever 240 to be raised. During each revolution of the arm 166, therefore, the lever 240 is raised twice, falling by gravity into contact with a set screw 260 each time that the cam 248 or the cam 250 rides beyond the lever.

So long as the recess 232 is out of reach of the pawl 234, the pawl rides idly up and down. As soon as the recess 232 is actuated into range of the pawl 234, however, the up movement of the pawl 234 will cause the counting disk 92 to be returned to its initial position. The counting disk will always be returned to the same initial position, irrespective of the particular position adjacent to the pawl 234 that the recess 232 may occupy—that is, irrespective of how many sheets more than 500 a counted ream may contain, as indicated by the position of the 5 indicator 158 relative to the index 230. This is because the upper limit of movement of the lever 240 is always the same.

The limits of movement, up and down, of the pawl 234 may, however, be adjusted. Adjustment is sometimes necessary to allow for wear and the like. The intermediate portion 246 of the lever 240 is provided with an elongated opening 252, shown more particularly in Fig. 11, into which extends one end of a stud 254, upon the other end of which is mounted a roll 256. The cams 248 and 250 engage the roll directly. The stud is secured in the elongated opening 252 by upper and lower set screws 258. By loosening one set screw 258 and tightening another, the vertical position of the stud 254 and, therefore, of the roll 256, may be adjusted, causing corresponding adjustment upward also, in the movement of the pawl 234.

It will be understood that the invention is not limited to the exact embodiment that is herein illustrated and described, and is subject to modification and change by persons skilled in the art. All such modifications and changes are considered to be within the spirit of the invention, and the scope of the invention is defined by the appended claims.

For clarity of illustration, the recess 232 is shown in Fig. 11 as provided in a second disk 89 secured to the counting disk 92 by a

What is claimed is:

1. A machine of the class described having, in combination, a counter adapted to

occupy an initial position, means for actuating the counter from the initial position to count a plurality of units, the counter being adapted to be actuated from the initial position to a degree corresponding to a plurality of units that is not a multiple of the first-named plurality of units, and means for returning the counter to the initial position upon the actuation of the counter from the initial position to the said degree.

2. A machine of the class described having, in combination, a counter having a counting element adapted to occupy an initial position, means for actuating the counting element from the initial position step by step to count a plurality of units at each step, the counting element being adapted to be actuated from the initial position to a degree corresponding to a plurality of units that is not a multiple of the first-named plurality of units, and means for returning the counting element to the initial position upon the actuation of the counting element from the initial position to the said degree.

3. A machine of the class described having, in combination, a centrally pivoted counting disk adapted to occupy an initial position, means for rotating the disk from the initial position about its pivot step by step to count a plurality of units at each step, the disk being adapted to be rotated about its pivot from the initial position to a degree corresponding to a plurality of units that is not a multiple of the first-named plurality of units, and means for completing the rotation of the disk throughout 360 degrees to cause the disk to return to the initial position upon the rotation of the disk from the initial position to the said degree.

4. A machine of the class described having, in combination, a centrally pivoted counting disk adapted to occupy an initial position and to be rotated about its central pivot to a degree corresponding to a predetermined arc along its circumference, the disk having a recess in its circumference positioned at the limit of the arc, means for rotating the disk from the initial position step by step to count a plurality of the units at each step, a pawl, and means for causing the pawl to enter the recess and for actuating the pawl to rotate the disk through an arc equal to 360 degrees minus the first-named arc to cause the disk to return to the initial position upon the actuation of the disk a number of steps corresponding to the first-named arc.

5. A machine of the class described having, in combination, a pivoted counting disk, means for rotating the disk about its pivot to a degree corresponding to a predetermined arc along its circumference, the disk being adapted to be rotated about its pivot

beyond the limit of the said arc, and means for rotating the disk to a predetermined position beyond the said limit of the arc upon the rotation of the disk to the said limit of the arc.

6. A machine of the class described having, in combination, a counter having a counting element adapted to occupy an initial position and to be actuated to count a plurality of units, means for actuating the counting element from the initial position step by step, and means for actuating the counting element to the initial position upon the actuation of the counting element a predetermined distance less than a step in excess of a whole number of steps.

7. A machine of the class described having, in combination, a counter adapted to occupy an initial position and to be actuated to count a plurality of units, a pawl for actuating the counting element from the initial position step by step, and a pawl for actuating the counting element to the initial position upon the actuation of the counting element a predetermined number of steps.

8. A machine of the class described having, in combination, a counter adapted to occupy an initial position, means for actuating the counter from the initial position to count a plurality of units, the counter being adapted to be actuated from the initial position to a degree corresponding to a plurality of units that is not a multiple of the first-named plurality of units, means for actuating the counter to the initial position upon the actuation of the counter from the initial position to the said degree, and means controlled by the first-named means for actuating the second-named means.

9. A machine of the class described having, in combination, a counter adapted to occupy an initial position and to be actuated to count a plurality of units, a pawl for actuating the counting element from the initial position step by step, a pawl for actuating the counting element to the initial position, an element upon which the first-named pawl is mounted, an element upon which the second-named pawl is mounted, and means controlled by the first-named element for actuating the second-named element.

10. A machine of the class described having, in combination, a counting disk having a gear and a recess, a gear meshing with the counting-disk gear, a ratchet movable with the meshing gear, a pawl for engaging the teeth of the ratchet, whereby actuation of the pawl effects actuation of the counting disk, a pawl adapted to enter the recess when the recess occupies a predetermined position, and means controlled by the first-named pawl for actuating the second-named pawl to cause the second-named pawl to engage the walls of the recess to effect actuation of the counting disk.

11. A machine of the class described having, in combination, a counting disk having a gear and a recess, a gear meshing with the counting-disk gear, a ratchet movable with the meshing gear, an arm having a cam and a pawl, the pawl being adapted to engage the teeth of the ratchet to effect actuation of the counting disk, a lever, and a pawl pivoted upon the lever adapted to enter the recess when the recess occupies a predetermined position, the cam being adapted to engage the lever to effect actuation of the second-named pawl to cause the second-named pawl to engage the walls of the recess to effect actuation of the counting disk.

12. A method of counting comprising actuating a counter from an initial position step by step to count a plurality of units at each step, the counter being adapted to be actuated from the initial position to a degree corresponding to a plurality of units that is not a multiple of the first-named plurality of units, and returning the counter to the initial position upon the actuation of the counter from the initial position to the said degree.

13. A machine of the class described having, in combination, means for operating upon articles in groups, and a counter for counting the number of articles that are operated upon, the counter comprising a counting element, and means for actuating the counting element a plurality of times corresponding to each operation upon the articles to count a plurality of units at each actuation of the counting element, the plurality of times being equal to the number of articles in each group divided by the plurality of units that are counted at each actuation of the counter.

14. A counter having, in combination, a counting tooth-controlled element, and a plurality of pawls for engaging the controlling teeth of the counting element to actuate the counting element, the parts being adjustable during the operation of the counter to effect the actuation of the counting element by each pawl to a proportional degree corresponding to a predetermined number of the controlling teeth of the counting element.

15. A counter having, in combination, a counting tooth-controlled disk, a plurality of pawls movable in one direction only along a circumference to engage the controlling teeth of the counting disk to actuate the counting disk, and means whereby each pawl is adapted to actuate the counting disk to a proportional degree corresponding to a predetermined number of the controlling teeth of the counting disk upon each movement of each pawl throughout the circumference.

16. A counter having, in combination, a

counting disk having a gear, a gear meshing with the counting-disk gear, a ratchet movable with the meshing gear, a plurality of pawls for engaging the teeth of the ratchet, whereby actuation of the pawls effects the actuation of the counting disk, a track located along a portion of the periphery of the ratchet, and means for actuating the pawls along the periphery of the ratchet, the pawls being adapted to run idly along the track during their actuation over the said portion of the periphery of the ratchet, whereby each pawl is adapted to actuate the ratchet through an angle corresponding to a proportional part of the remaining portion of the periphery of the ratchet upon each actuation of each pawl.

17. A counter having, in combination, a shaft adapted to be continuously rotated, an arm extending from and rotating with the shaft, a plurality of pawls mounted upon the arm, a ratchet wheel loosely mounted on the shaft the teeth of which are adapted to be engaged by the pawls, whereby the ratchet wheel is adapted to be rotated about the shaft by the pawls, a plurality of segmental members having cam tracks over which the pawls are adapted to ride idly, the segmental members being adjustable to expose a variable number of teeth of the ratchet wheel, whereby each pawl is adapted to actuate the ratchet wheel through an arc corresponding to a proportional part of the number of teeth exposed upon each rotation of the pawl, a pinion secured to the ratchet wheel so as to rotate therewith, a counting disk having gear teeth meshing with the teeth of the pinion, and an indicator for the counting disk.

18. A method of counting a number of articles that are simultaneously operated upon in groups comprising actuating a counter from an initial position step by step, each step of actuation of the counter corresponding to an operation upon the articles, the counter counting a plurality of units at each step, the counter being adapted to be actuated from the initial position to a degree corresponding to a plurality of units that is not a multiple of the first-named plurality of units, and returning the counter to the initial position upon the actuation of the counter to the said degree.

19. A machine of the class described having, in combination, means for operating upon articles in groups, and a counter for counting the number of articles that are operated upon, the counter comprising a counting element having an initial position, means for actuating the counting element from the initial position a plurality of times corresponding to each operation upon the articles to count a plurality of units at each actuation of the counting element, the

plurality of times being equal to the number of articles in each group divided by the plurality of units that are counted at each actuation of the counter, the counting element being adapted to be actuated from the initial position to a degree corresponding to a plurality of units that is not a multiple of the first-named plurality of units,

and means for returning the counting element to the initial position upon the actuation of the counting element to the said degree. ¹⁰

In testimony whereof, I have hereunto subscribed my name this 18th day of July, 1924.

CHARLES B. MAXSON.
